 Radio Corporation of America, a corporation of
 Delaware

Application February 9, 1944, Serial No. 521,633

13 Claims. (Cl. 179—171)

This invention concerns improvements in high power radio transmitters.

The primary object of the present invention is to provide a simplified, compact radio transmitter of high power and of reduced cost compared with known types of transmitters of the same power rating.

A feature of the invention resides in a novel construction employing a metallic panel maintained at the same D.-C. potential as the associated vacuum tube stage and which supports the elements comprising the output tank and filter. This construction makes use of a common radio frequency bypass condenser, thus eliminating the necessity for a multiplicity of bypass condensers which would ordinarily be required for the various network circuit elements, and improves the operation of the associated vacuum tube stage by reducing the tendency to the generation of parasitic oscillations.

Another advantage of this novel construction is that it enables the circuit to be fully effective in suppressing undesired harmonics produced by the associated vacuum tube stage.

A more detailed description of the invention follows in conjunction with the drawings wherein

Figure 1 illustrates schematically a known type of high power radio transmitter;

Figure 2 illustrates the novel mechanical and electrical structure of the transmitter of the present invention; and

Figure 3 schematically illustrates the equivalent electrical circuit of the transmitter of Fig. 2.

Referring to the system of Fig. 1, which exemplifies known practice, there is shown that portion of a high power transmitter which couples a push-pull amplifier stage 2, 4 to a suitable transmission line extending to a load such as an antenna. The vacuum tubes 2 and 4 are shown as triodes whose grids are coupled to opposite terminals of a parallel tuned circuit 21 to which is supplied radio frequency energy from a suitable input circuit. In practice, the radio frequency input circuit would include one or more driving amplifier stages whose inputs are coupled to a highly stable low power oscillator. The anodes of the push-pull power amplifier 2, 4 are connected to a pair of pi networks A and B. Pi network A is, in reality, the main tank circuit, while network B serves as a harmonic attenuator and load adjustor. The output of network B is supplied through blocking condensers 15 and 17 to a suitable transmission line coupling the power amplifier to the load.

A large portion of the capacity for pi network A is made up of the anode to cathode interelectrode tube capacities shown in dotted lines and labeled by the reference numerals 6, 8. The interelectrode vacuum tube capacities 6, 8 are essential elements of the input capacity to the pi network A in the particular system shown. Coils 10 and 12 are removable plug-in coils for enabling the power amplifier tubes 2, 4 to be used with different frequency bands. Condensers 14, 16 are motor driven variable multi-plate air condensers. Condensers 18, 20, 22 and 24 are fixed condensers of adequate rating and may, if desired, be of the mica or sulphur filled type.

The alternating voltage at the anodes of the tubes 2, 4 may be of the order of 6,000 or 7,000 volts, and this alternating voltage is reduced at points 26, 28 to the order of only 1,500 volts due to the impedance transfer property of the network A. Anode polarizing potential is supplied to the anodes over lead 36, which connects to the midpoint of choke coil 30 connected across the two sides of the network B. This D.-C. potential may be of the order of 6,000 volts. With the arrangement shown, it is not possible to directly connect the junction points between condensers 14 and 16 and between condensers 22 and 24 to ground unless these condensers are built to withstand both the direct current and the alternating voltages to which the circuits are subjected. With the voltage values indicated above, the combined direct current and alternating voltages across condensers 22 and 24 and across condensers 14 and 16 would amount to a peak value above 7,500 volts. To enable these condensers to withstand this high peak value of voltage entails relatively costly construction. In the alternative, these condensers 14, 16, 22, 24 can be designed to withstand only the alternating voltage, in which case there would be required the additional bypass grounding condensers 32 and 34, the latter, in turn, designed to withstand the 6,000 volts of anode polarizing potential impressed on the circuit by lead 36. In this last case, which is the situation illustrated in the system of Fig. 1, additional resistors 7, 9 are employed to assure that all of the D.-C. voltage is impressed across the bypass condensers 32, 34. Although condensers 32 and 34 eliminate the necessity for making condensers 14, 16, 22 and 24 of high rating, these grounding condensers are objectionable since they encourage and actually give rise to parasitic oscillations.

Also, condensers 18 and 20, which are sometimes used as padding condensers, must be de-

signed for high voltage rating and therefore are costly or, in the alternative, they require a separate bypass condenser 40 connected to ground. The use of condenser 40 also gives rise to parasitics and requires additional resistors 11, 13 for the same purpose described above in connection with resistors 7, 9.

By way of further explanation, bypass or grounding condensers 32, 34 and 40 set up parasitics because they resonate with the inductance of the leads to the various circuit elements. These grounding condensers are further objectionable since they serve to partially suppress and nullify the effectiveness of the pi networks A and B. This follows because of the fact that the harmonics generated by the tubes 2 and 4 have a tendency to remain in and flow through the various condenser leads rather than be confined to the pi networks. It is for this reason that the inductance in the leads to the grounding condensers act to nullify the desired, short, low impedance paths to ground from the junction points of the network tuning capacitors 14, 16, 18, 20, and 22, 24.

The foregoing difficulties and objectionable features in the known circuit of Fig. 1 are overcome in the present invention by the construction shown in Fig. 2. Throughout all figures of the drawings, the same parts are designated by the same reference numerals.

In Fig. 2 there is provided a metallic mounting or support panel or plate 50 which is arranged vertically and serves to support the various circuit components of the pi networks A and B as modified in the manner described hereinafter. Panel 50 is insulatingly spaced from a metallic vertically arranged ground plate 70 by means of stand-off insulators 54, 56. Four of these insulators are provided, as shown, to support the plate 50 from the ground plate 70. Panel 50 is maintained at the high 6,000 volts D.-C. anode potential supplied through lead 36, and this panel is grounded for radio frequencies by means of a common bypass condenser 68. This common bypass condenser not only grounds the panel 50 for radio frequency energy, but also replaces the various grounding condensers 32, 34 and 40, shown in Fig. 1, and eliminated from the circuit of Fig. 2. For reasons which will appear in more detail later, the insulators and condensers supporting the circuit elements on the panel 50 are designed only to withstand the alternating component of the radio frequency voltages in the circuit. The stand-off insulators for the panel 50 are relatively inexpensive, few in number, and need, in general, withstand only the D.-C. voltage applied to the common supporting panel 50.

The vacuum tubes 2 and 4 are shown mounted in the rear of the panel 50, and the anode connections from these two tubes extend through holes 69 in the panel 50 for connection to the plug-in coils 10, 12. The plug-in coils 10, 12 are supported by means of stand-off insulators 58, 59. The variable condensers 14, 16, respectively, are connected at one terminal to the metallic panel 50 and at the other terminal to the coils 10 and 12. These condensers are here shown as being multi-plate air condensers which are variable and driven by a motor arrangement not shown. Those terminals of condensers 14 and 16 which are directly connected to the coils 10 and 12 are also connected through fixed condensers 18, 20 to radio frequency ground plate 50. It will thus be seen that the condensers 18 and 14 are in parallel relation while the condensers 20 and 16 are also in

parallel relation on opposite sides of the network. The condensers 14 and 16 serve both as output capacitors for the network A and as input capacitors for the network B. Condensers 18, 20 are padding condensers to extend the frequency range. The inductors 60 and 62 are supported by stand-off insulators 61, 64 and their terminals on insulators 64 are connected to the ungrounded terminals of harmonic attenuator condensers 22, 24.

Condensers 22 and 24 are fixed and their other terminals are directly connected to the metallic panel 50. The high positive D.-C. potential for the anodes of the vacuum tubes 2 and 4 is supplied from source +B through lead 36 which connects to the midpoint of choke coil 30, the latter, in turn, being positioned across the condensers 22 and 24, as shown. The center tap of choke coil 30 is connected to the metallic panel 50 through a resistor 52, thus maintaining the panel 50 at the same high D.-C. potential as the anodes of vacuum tubes 2 and 4. Blocking condensers 15 and 17, which couple the B network to the load, are supported on stand-off insulators 65 and 67.

A better understanding of the operation of Fig. 2 may be had by referring to the equivalent electrical circuit diagram of Fig. 3. It will be seen from an inspection of Fig. 3 that the metallic panel 50 is maintained at the high positive D.-C. anode potential and that no current flows through resistor 52 under steady state conditions because the supporting panel 50 is insulatingly supported from ground for unidirectional currents by virtue of the stand-off insulators 54, 56. Because of the fact that the anode polarizing potential from lead 36 appears both on the panel 50, which is connected to one side of each of condensers 14, 16, 18, 20 and also appears on the other side of these same condensers, it will be apparent that there is no D.-C. potential difference across these condensers and there is no necessity to design these condensers to withstand a high D.-C. potential, as was the case in Fig. 1. These condensers 14, 16, 18 and 20, however, need be designed to withstand only the radio frequency components of the voltages in the circuits as they arise at the supporting points corresponding to the terminals of inductors 10, 12 and 60, 62. It should be noted that the system of Figs. 2 and 3 eliminates the necessity for the use of grounding condensers 32, 34 and 40 of Fig. 1 and also eliminates the necessity for the use of resistors 7, 9, 11 and 13.

In one embodiment of the invention successfully tried out in practice, the system of Fig. 2 formed an essential part of a 7.5 kw. transmitter operating in the range from 2.5 to 25 megacycles, depending upon the choice of inductors and capacitors. The anode D.-C. potential supplied to the choke 30 was of the order of 6,000 volts. The vacuum tubes 2 and 4 were RCA 889R tubes having an elongated anode supplied with fins for air cooling. The radio frequency input to the grids of the push-pull tubes 2 and 4 was supplied from a highly stable low power oscillator generating oscillations of 2.5 megacycles. Several stages of amplification and, if desired, multiplication were provided between the output of the oscillator and the input of the power amplifier 2, 4. It should be understood that various modifications may be made in the system of the invention without departing from the spirit and scope thereof. For example, the mounting panel 50 can be designed to have sufficient area and by suitable spacing relative to the ground plate 70,

the panel 50 itself can be made to perform the function of the bypass capacitor 68, which can then be omitted. Moreover resistor 52 can be omitted, although its use is preferred to prevent the possibility of "sneak" parasitics. Suitable modulation can be supplied to lead 38, or to any other preferred portion of the transmitter in known manner. The system of the invention is not limited to use between a power amplifier and a load, but may be used between two vacuum tube stages of a transmitter.

What is claimed is:

1. High power high frequency apparatus including a vacuum tube stage and a utilization circuit, a network in the output of said stage, said network having a plurality of condensers thereacross, a direct connection between one terminal of one of said condensers and a terminal of another of said condensers, said direct connection comprising a mounting panel for supporting said network, a source of anode polarizing potential and means for supplying said potential to said stage through said network, a direct current connection from said source to said panel, said panel being effectively by-passed to a point of zero radio frequency potential for energy of the operating frequency.

2. High power high frequency apparatus including a vacuum tube stage and a utilization circuit, a network coupling the output electrode of said stage to said utilization circuit, said network including a coil and a pair of condensers parallelly connected, one terminal of said parallel combination being connected to one terminal of said coil, the other terminal of said parallel combination being connected to a metallic mounting panel, stand-off insulating means supporting said coil from said panel, a source of polarizing potential for the output electrode of said stage connected to one terminal of said coil, a direct current connection from said source to said panel, and means for by-passing said panel to a surface of zero radio frequency potential for energy of the operating frequency.

3. A high power transmitter comprising a triode vacuum tube, a network comprising a coil having one terminal connected to the anode of said tube and the other terminal coupled to a utilization circuit, the interelectrode capacity of said tube constituting the input capacity of said network, a metallic panel supporting said coil by insulating means positioned between the coil and panel, an output capacitor for said network comprising a condenser one electrode of which is connected to said last terminal of said coil and the other electrode of which is connected to said panel, a source of direct current potential, a connection from the positive terminal of said source to said coil for supplying polarizing potential to the anode of said tube, and a direct current connection from said source to said panel, whereby the electrodes of said condenser have substantially the same direct current potential applied thereto, said panel being by-passed to ground for energy of the operating frequency.

4. A high power transmitter comprising a push-pull amplifier stage, including a pair of vacuum tubes, a source of radio frequency energy coupled to the input electrodes of said tubes, a network including a pair of coils connected to different output electrodes of said tubes and coupling said tubes to a utilization circuit, a pair of condensers connected in series across those terminals of said coils farthest removed from said output electrodes, a metallic panel supporting the compo-

nent parts of said network, stand-off insulators supporting said coils from said panels, each of said condensers having one terminal directly connected to one terminal of a coil and the other terminal directly connected to said panel, whereby said panel forms the electrical junction for said condensers, a source of direct current polarizing potential for the output electrodes of said tubes, separate direct current connections from said source to said coils and panel, and a single by-pass condenser coupling said panel to a surface of zero radio frequency potential.

5. A high power radio transmitter comprising a push-pull amplifier stage comprising a pair of vacuum tubes, a source of radio frequency energy coupled to the input electrodes of said tubes, a load circuit, and a pair of pi networks in series coupling the anodes of said tubes to said load, each of said networks including an inductor coil in each side thereof, a condenser from each side of each of said networks to a common metallic surface, a source of anode direct current polarizing potential for said vacuum tubes connected to the two sides of that pi network nearest the load, and a direct current connection from said source of polarizing potential to said common metallic surface, whereby said condensers need only be able to withstand the alternating voltage from said amplifier stage, said surface being by-passed to ground for energy of the operating frequency.

6. A radio transmitter including a vacuum tube stage, a utilization circuit therefor, a pi network coupling the output electrode of said stage and said utilization circuit, said network including a coil and a condenser at each end of said coil, a metallic surface connecting together one terminal of one condenser and the corresponding terminal of the other condenser, a source of direct current polarizing potential for the output electrode of said tube connected to that end of said coil farthest removed from said vacuum tube, and a direct current connection from said source to said metallic surface, said surface being by-passed to ground for energy of the operating frequency.

7. A high power radio transmitter comprising a push-pull amplifier stage comprising a pair of vacuum tubes, a source of radio frequency energy coupled to the input electrodes of said tubes, a load circuit, and a pair of pi networks in series coupling the anodes of said tubes to said load, each of said networks including an inductor coil in each side thereof, a condenser from each side of each of said networks to a metallic panel, a source of anode direct current polarizing potential for said vacuum tubes connected to the two sides of that pi network nearest the load, a direct current connection from said source of polarizing potential to said panel, whereby said condensers need only be able to withstand the alternating voltage from said amplifier stage, a ground surface behind said panel, and a radio frequency by-pass condenser coupling said panel to said ground surface.

8. A high power radio transmitter comprising a push-pull amplifier stage comprising a pair of vacuum tubes, a source of radio frequency energy coupled to the input electrodes of said tubes, a load circuit, and a pair of pi networks in series coupling the anodes of said tubes to said load, each of said networks including an inductor coil in each side thereof, a condenser from each side of each of said networks to a metallic panel, a source of anode direct current polarizing poten-

tial for said vacuum tubes connected to the two sides of that pi network nearest the load, a direct current connection from said source of polarizing potential to said panel, whereby said condensers need only be able to withstand the alternating voltage from said amplifier stage, stand-off insulators supporting said inductor coils from said panel, said condensers being mounted on said panel, a ground surface behind said panel, said tubes being mounted on said ground surface, and a radio frequency by-pass condenser coupling said panel to said ground surface.

9. A radio transmitter in accordance with claim 6, characterized in this that said metallic surface is a vertical panel which supports said pi network.

10. A high power radio transmitter including a push-pull amplifier stage comprising a pair of triode vacuum tubes, a load, first and second pi networks in series relation coupling the anodes of said stage to said load, the interelectrode capacity of said tube stage constituting the input capacity of said first network, each of said networks including an inductor coil in each side thereof, a condenser connecting each side of each of said networks at the output end thereof to a common metallic panel, the elements of said networks being supported by said panel, a choke coil across the output end of said second pi network, a source of direct current polarizing potential for the anodes of said tubes connected to the midpoint of said choke coil, and a direct current connection from said source to said panel, said panel being by-passed to ground for energy of the operating frequency.

11. A radio transmitter including a vacuum tube stage, a utilization circuit therefor, a coil coupling the output electrode of said stage and said utilization circuit, a condenser at each end of said coil, a metallic surface connecting together one terminal of one condenser and the corresponding terminal of the other condenser, a source of direct current polarizing potential for the output electrode of said tube connected to that end of said coil farthest removed from said vacuum tube, and a direct current connection from said source to said metallic surface, said surface forming a panel supporting said coil and

condensers and being by-passed to ground for energy of the operating frequency.

12. High power high frequency apparatus comprising a vacuum tube, a high frequency output circuit comprising an inductor having one terminal connected to the anode of said tube and another terminal through which anode potential is supplied to the anode of the tube, a metallic panel supporting said inductor by insulating means positioned between the inductor and panel, a capacitor for said high frequency circuit comprising a condenser one electrode of which is connected to a terminal on said inductor and the other electrode of which is connected to said metallic panel, a source of direct current potential, a connection from the positive terminal of said source to said inductor for supplying polarizing potential to the anode of said tube, a direct current connection from said source to said panel, whereby the electrodes of said condenser have substantially the same direct current potential applied thereto, and a by-pass condenser connected to said panel and to ground for effectively grounding said panel at the operating frequency.

13. High frequency apparatus comprising a push-pull amplifier stage, including a pair of vacuum tubes, a source of radio frequency energy coupled to the input electrodes of said tubes, a network including a pair of inductors connected to different output electrodes of said tubes and coupling said tubes to a utilization circuit, a pair of condensers connected in series across a pair of terminals of said inductors, a metallic panel supporting the component parts of said network, stand-off insulating means supporting said inductors from said panel, each of said condensers having one terminal directly connected to one terminal of one of said inductors and the other terminal directly connected to said panel, whereby said panel forms the electrical junction for said condensers, a source of direct current polarizing potential for the output electrodes of said tubes, direct current connections from said source to said inductors and panel, and a by-pass condenser connecting said panel to ground for high frequency currents.

JOHN E. YOUNG.
